UNITED STATES PATENT OFFICE.

GEORGE W. FULLERTON, OF McMECHEN, WEST VIRGINIA.

RAIL JOINT.

Application filed May 26, 1922. Serial No. 563,886.

To all whom it may concern:

Be it known that I, GEORGE W. FULLERTON, a citizen of the United States, residing at McMechen, in the county of Marshall and 5 State of West Virginia, have invented new and useful Improvements in Rail Joints, of which the following is a specification.

My present invention has reference to means for connecting the confronting ends 10 of railway rails.

My object is to produce a connecting means for railway rails which shall be of an extremely simple construction, wherein the employment of bolts passing through 15 and weakening the webs of the rails will be entirely dispensed with, and wherein the rails will have a wedging engagement with the joint that supports the ends thereof.

A further object is to produce a wedge 20 joint for railway rails which may not only successfully be employed in connecting the ends of rails, but which may be also employed as an effective splice for broken rails.

The foregoing objects may be accomplished by a construction, combination and operative association of parts such as is disclosed by the drawings which accompany 25 and which form part of this application.

In the drawings:

30 Figure 1 is a plan view of two rails having their ends connected in accordance with this invention.

Figure 2 is a side elevation thereof.

Figure 3 is a sectional view on the line 35 3—3 of Figure 1.

Figure 4 is a perspective view of one of the angle wedge members.

It will be noted, as the description progresses, that rail ends supported in accordance 40 with my invention will be held from tilting or vertical movement, but will be permitted the necessary longitudinal movement necessary for expansion and contraction.

Referring now to the drawing in detail 45 the numeral 1 designates ties for rails 2—2. Resting on the ties 1 is the flat chair member 3 of my improvement. The chair, at a suitable distance inward of its edges is formed with upwardly directed flanges 4 and 5 respectively. The flanges 4 and 5 extend the 50 length of the chair and the confronting faces thereof are arranged angularly with respect to the axial plane of the base of the chair, the said confronting faces being parallel. Thus the diagonally opposed ends of the flanges are wider at one end than at the

other, and for distinction, the wider end of the flange 4 is indicated by the numeral 6 and that of the flange 5 by the numeral 7. The said confronting faces of the flanges 4 and 5 are undercut. While not illustrated by the drawing the distance between the confronting faces of the flanges may be sufficient to permit of the passing of the flanges of the rails therebetween. 65

The means for securing the rail ends in the chair comprise a pair of angle fish plates, each of which being of a similar construction and has its parts referred to by similar reference characters in the drawing. Each fish plate includes a base 8 whose outer edge is formed with an angular upstanding flange 9. The inner face of the flange 9 is longitudinally concaved, as at 10, the said flange 9 having its inner face provided with an angle incut portion 11, at its juncture with the base 8 whereby to receive the edges of the base flanges of the rails, the vertical flange 9 being of a height to contact with the under faces of the heads of the rails, the inner 75 faces of the said flanges being shaped to contact with the webs of the rails, while the concaved depressions or grooves 10 permit of a yieldability of the vertical flanges 9 so that an abrupt contact therewith will not occur when the wheels of weighted rolling stock pass over the joint. To more materially assist in this connection the outer but upper portion of each of the vertical flanges of the angle fish plates is reduced, being 80 rounded inwardly for its entire length, as indicated by the numeral 12, and from the juncture of the said concaved or inwardly rounded portions 12 to the lower edges of the flanges 10 the outer faces of the said 85 flanges are cut at a downward and outward inclination, as indicated by the numeral 13. The downwardly inclined faces 13 of the flanges gradually increase in thickness from one end of the angle fish plate to the other 90 end thereof, and the inclination of the said flanges corresponds with the inclined inner face of the flanges 4 and 5. At their narrower ends the beveled and inclined faces 13 of the angle wedge fish plates are formed with 95 notches 14.

In practice, one of the wedge fish plates may be arranged in the chair and the rails may rest upon the base 8 thereof. The second wedge fish plate is then inserted from 100 the wider space between the flange 4 or 5 and the webs of the rails. It is, of course,

obvious that a force of pressure must be exerted upon the thickened end of the last mentioned wedge fish plate, but when the same is fully driven home the notch 14 thereof 5 will register with an angular opening 15 adjacent to the diagonally opposed corners of the chair 3, the opposite corners being provided with straight openings 16. All of the openings enter the flanges 4 and 5, and passing 10 through the first mentioned openings 15 are angularly arranged spikes 17 which, of course, also enter the ties 1, similar spikes 18 being driven through the straight openings 16 and entering the tie. In this manner 15 the joint effectively engages the rails and is effectively secured on the ties.

While my improvement is particularly designed as a joint for the confronting ends of rails and is adapted to minimize time and 20 labor expended in connecting the said rails, as well as to dispense with the employment of the bolts and nuts and the weakening effect thereof upon both the joint and rail ends, the improvement may be employed 25 with equal efficiency as a splice for broken rails.

Having described the invention, I claim:

In a rail joint, the combination with ties 30 and the confronting ends of rails, of a chair member supported on two of the ties to receive therein the rail ends, said chair, adjacent its edges having upstanding flanges

whose inner walls are disposed at an inward inclination, said flanges having their 35 inner faces arranged angularly with respect to the axial plane of the base of the chair and their said inner faces parallel and undercut, wedge plates each including a flat base to be received on the base of the chair 40 and on which the base flanges of the rails rest, each of said plates having its outer edge formed with a vertical flange which is centrally concaved inwardly and is recessed 45 downwardly and outwardly from its said concavity to receive the edges of the base flanges of the rails therein, said vertical plates contacting with the under faces of the heads of the rails and having their upper portions rounded inwardly throughout their 50 lengths and from thence beveled outwardly and downwardly, said last mentioned portions gradually decreasing in width from one to the opposite end thereof whereby the same may be inserted in the chair from opposite ends thereof respectively to contact 55 with the opposed inclined faces of the flanges, the reduced outer edge of each of the wedge members being notched, the chair having diagonally opposed angular openings 60 designed to register with the notches and to receive spikes therethrough which enter the ties, and other spikes also passing through the chair and entering the ties.

In testimony whereof I affix my signature.

GEORGE W. FULLERTON.
